UNITED STATES PATENT OFFICE

2,450,205

COMPRESSIBLE POWDER DISPENSER

William H. Rose, Jersey City, N. J.; Hudson County National Bank, executor of said William H. Rose, deceased

Application January 8, 1946, Serial No. 639,778

7 Claims. (Cl. 222—193)

1

My invention relates to powder dispensers and refers particularly to those adapted for the emission of powder therefrom by means of applied air pressure.

One of the objects of my invention is the inclusion of air-pervious, powder impervious materials adapted to allow of the passage of air therethrough while preventing the passage of powder therethrough.

Another object of my invention is powder devices in which an air-pervious, powder impervious material is so positioned as to prevent the clogging of the air-delivery tubes and the powder-exit tubes during use and storage.

Another object of my invention is to agitate a powder within a container both during pressure to cause the powder to be ejected from the container and during the release of said pressure.

It is well recognized that the presence of powder in any of the air passages in devices of this character will have a tendency to pack and thus clog these passages to an extent that will greatly decrease, if not completely retard the efficiency of the device.

It is well known, further, that as the interior end of a powder-exit tube must be positioned in the lower portion of the container in order to remove as much powder as possible, this portion of the powder mass becomes packed and hence difficult to remove.

The devices of my invention are directed to overcome the mentioned and other undesirable features of my powder dispensers, and I herein-after show and explain that I have overcome these undesirable features.

In the accompanying drawings of modified forms of the devices of my invention, similar parts are designated by similar numerals.

Figure 1 is a vertical section of one form of a device of my invention.

Figure 2 is a section through the line 2—2 of Figure 1.

Figure 3 is a vertical section through a modified form of a device of my invention.

Figure 4 is a section through the line 4—4 of Figure 3.

Figure 5 is a plan view of the air-delivery tube shown in Figs. 3 and 4.

The particular form of a device of my invention shown in Figures 1 and 2 of the accompanying drawings comprises a tubular casing having the resilient side member 10, the rigid top member 11 and the rigid bottom member 12, the side member being fixedly attached to the top member 11 by means of the annular channel 13

of the top member and the side member being fixedly attached to the bottom member 12 by means of the annular channel 14 of the bottom member.

It will be noted that the central portion of the side member 10 can be pressed inwardly and will return to its natural position upon the release of said pressure.

The side member 10 may consist of a single sheet, a plurality of superimposed sheets or a sheet wrapped upon itself to form a laminated sheet of a suitable resilient material, among which are rubber, cardboard, metal and synthetic resins.

Positioned within the casing and supported by the top member 11 is a powder-exit tube 15, the upper end of the tube 15 being open outwardly at the casing and the lower end of the tube 15 being positioned above the bottom member 12.

Positioned longitudinal to the exit tube 15 and abutting thereon is an air-circulating tube 16. Positioned over each of the openings of air-circulating tube 16, and fixedly attached thereto, is a disc of air-pervious, powder impervious material 17, among which materials are felt, fibers, materials, glass sponge, wood and cellulose fibers, in such physical construction as to allow of the passage of air therethrough and prevent the passage of powder therethrough upon the compression of the side of the container and upon the release of such pressure allow the side to return to its original position.

The powder-exit tube 15 and the air-circulating tube 16 are maintained in the desired position with respect to each other by means of clamps 18, 18.

The operation of the device is as follows: a fine powder 19 is introduced into the device and, the central portion of the tubular member side is pressed inwardly, thus forcing the air from the air from the air chamber 20, through the upper air-pervious, powder-impervious material 17 thence through the air circulating tube 16, thence through the lower air pervious, powder impervious material 17 into the powder mass 19. This forced passage of air will agitate the powder in the lower portion of the device and will thence pass outwardly of the device through the powder-exit tube, carrying a portion of the powder 19 with it.

Upon release of the pressure upon the side of the device, air will be withdrawn inwardly through the powder-exit tube 15 into and agitating the powder mass 19 and thence upwardly through the powder mass 19 and the air-circulating tube 16 into the air chamber 20.

It will be noted that during the last described operation, the lower air-pervious, powder-impervious material 17 will allow of the passage of air through the tube 16, but will prevent the powder from entering it, thus preventing clogging thereof.

It will also be noted that the upper air-pervious, powder-impervious material will prevent the powder from entering the air-circulating tube when the device is agitated during shipment or storage, or when the device is positioned otherwise than in its normal upright position.

The construction of my devices and the composition of their elements prevent, therefore, the entrance of the powder into the air-circulating tube 16, thus preventing the powder from clogging the tube, while allowing passage of air therethrough to allow of the emission of powder through the powder-exit tube 15.

The modified form of a device of my invention shown in Figures 3 and 4 of the drawings is similar to that shown in Figures 1 and 2 as evidenced by the corresponding numerals, differing therefrom, however, as follows:

In this form of my device the powder-exit tube 15 is positioned vertically through the air-circulating tube 22 and the upper end of the air-circulating tube is closed by means of a disc of air-pervious, powder-impervious material 17, fixedly attached thereto with a central opening 23 therethrough for the inclusion of the powder-exit tube 15. The lower end of the air-circulating tube 27 is closed by means of a disc 24 similar to that employed for the closing of its upper end, except that the disc is positioned between the side of the air-circulating disc 27 and the side of the powder-exit tube 15 and may be frictionally retained therein or may be adhesively attached thereto.

It will thus be seen that my invention presents powder dispensing devices, operable by compression of its side member and in which there is an air-pervious, powder non-impervious element preventing the powder from clogging its necessary air passage while allowing the passage of air to accomplish its practical application.

I do not limit myself to the particular size, shape, number, arrangement or material of parts as specifically shown and described, as these may be varied within the scope of my invention.

What I claim is:

1. A powder dispenser comprising an elongated casing having flexible resilient side members and rigid end members; a powder-exit hollow tubular member open at both ends and having its upper open end positioned outside said casing adjacent one end member and its lower open end positioned inside said casing adjacent the other end member, thus forming an exit opening for said casing; an air-circulating tubular member within said casing, the lower end of which is adjacent to the lower end of said powder-exit member and means adapted to allow the passage of air through said air-circulating tubular member while preventing the passage of powder therethrough.

2. A powder dispenser comprising an elongated casing having flexible resilient side members and rigid end members; a powder-exit hollow tubular member open at both ends and having its upper open end positioned outside said casing adjacent one end member and its lower open end positioned inside said casing adjacent the other end member, thus forming an exit opening for said casing; an air-circulating tubular member within said casing, the lower end of which is adjacent to the

lower end of said powder-exit member, means adapted to maintain said powder-exit member and said air-circulating member adjacent to each other, and means adapted to allow the passage of air through said air-circulating tubular member while preventing the passage of powder therethrough.

3. A powder dispenser comprising an elongated casing having flexible resilient side members and rigid end members; a powder-exit hollow tubular member open at both ends and having its upper open end positioned outside said casing adjacent one end member and its lower open end positioned inside said casing adjacent the other end member, thus forming an exit opening for said casing; an air-circulating tubular member within said casing, the lower end of which is adjacent to the lower end of said powder-exit member and means adapted to close the ends of said air-circulating member and allowing the passage of air through said air-circulating tubular member while preventing the passage of powder therethrough.

4. A powder dispenser comprising an elongated casing having flexible resilient side members and rigid end members; a powder-exit hollow tubular member open at both ends and having its upper open end positioned outside said casing adjacent one end member and its lower open end positioned inside said casing adjacent the other end member, thus forming an exit opening for said casing; an air-circulating tubular member within said casing, the lower end of which is adjacent to the lower end of said powder-exit member and air-pervious, powder-impervious means carried by said air-circulating member adapted to allow the passage of air through said air-circulating tubular member while preventing the passage of powder therethrough.

5. A powder dispenser comprising an elongated casing having flexible resilient side members and rigid end members; a powder-exit hollow tubular member open at both ends and having its upper open end positioned outside said casing adjacent one end member and its lower open end positioned inside said casing adjacent the other end member, thus forming an exit opening for said casing; an air-circulating tubular member within said casing, the lower end of which is adjacent to the lower end of said powder-exit member and air-pervious, powder-impervious means carried by said air-circulating member adapted to close the ends of said air-circulating member and allow the passage of air through said tubular member while preventing the passage of powder therethrough.

6. A powder dispenser comprising an elongated casing having flexible resilient side members and rigid end members; a powder exit hollow tubular member open at both ends and having its upper open end positioned outside said casing adjacent one end member and its lower open end positioned inside said casing adjacent the other end member, thus forming an exit opening for said casing; an air-circulating tubular member within said casing, the lower end of which is adjacent to the lower end of said powder-exit member, said powder-exit member being positioned longitudinally within said air-circulating member and air-pervious, powder-impervious means adapted to close the ends of said air-circulating member and allow the passage of air through said air-circulating tubular member while preventing the passage of powder therethrough.

7. A powder dispenser comprising an elongated casing having flexible resilient side members and

rigid end members; a powder-exit hollow tubular member open at both ends and having its upper open end positioned outside said casing adjacent one end member and its lower open end positioned inside said casing adjacent the other end member, thus forming an exit opening for said casing; an air-circulating tubular member within said casing, the lower end of which is adjacent to the lower end of said powder-exit member, said powder-exit member being positioned longitudinally within said air-circulating member and air-permeous, powder-impervious means carried by said air-circulating member adapted to close the ends of said air-circulating member and allow the passage of air through said air-circulating tubular member while preventing the passage of powder therethrough. 15
